(57) CLAIM

I claim the ornamental design for an adult toy, as shown and described.

DESCRIPTION

FIG. 1 is a top, front perspective view of a massager component and ring component of the adult toy embodying the new design.

FIG. 2 is a rear view of the massager component of the adult toy embodying the new design.

FIG. 3 is a front view of the massager component adult toy embodying the new design.

FIG. 4 is a top view of the massager component of the adult toy embodying the new design.

FIG. 5 is a bottom view of the massager component of the adult toy embodying the new design.

FIG. 6 is a right side view of the massager component of the adult toy embodying the new design.

FIG. 7 is a left side view of the massager component of the adult toy embodying the new design.

FIG. 8 is a top, front perspective view of a ring component of the adult toy embodying the new design.

FIG. 9 is a top perspective view of a ring component of the adult toy (which is a mirror image of the bottom, right side, and left side views of the ring component) embodying the new design; and,

FIG. 10 is a front view of a ring component of the adult toy (which is a mirror image of the rear view of the ring component) embodying the new design.

The shading lines shown in the drawings represent the approximate three-dimensional contour of the design, and are not intended to indicate surface decoration.

The broken lines shown in the drawings are for the purposes of illustrating portions of the adult toy that form no part of the claimed design.
